APPARATUS HAVING SEPARATEABLE AND ASSEMBLABLE PORTIONS AND CONTROL MEANS THEREFOR

Samuel A. Huffman, Pasadena, Calif., assignor to
 Miller Printing Machine Co., Pittsburgh, Pa., a
 corporation of Pennsylvania

Continuation of application Serial No. 406,800,
 August 14, 1941. This application July 11, 1945,
 Serial No. 604,448

5 Claims. (Cl. 271—8)

1

This invention relates to apparatus having separable and assemblable portions and control means therefor. It relates particularly to apparatus comprising portions relatively movable toward and from cooperative relation in which they are adjacently positioned. The invention has to do primarily with means for effecting and stopping relative movement between such portions and connections facilitating such relative movement, relieving the parts of strain and providing for the safety of workmen. This application is a continuation of my copending application Serial No. 406,800 now abandoned.

The invention is of wide application to apparatus having separable and assemblable portions. I have adapted it particularly to printing apparatus wherein it has important advantages. However, I regard the invention as having particular advantages when applied to material handling apparatus of various kinds, including, of course, sheet handling apparatus. The term "material handling apparatus" is used herein as a term of broad definition and not of limitation and comprehends any apparatus in which material of any character is handled or treated. Purely for purposes of explanation and illustration the invention will be described as embodied in printing apparatus. The word "printing" as used herein comprehends not only the application of ink to sheets but also analogous treatment thereof customarily performed in similar apparatus as, for example, cutting and creasing.

I have found that the invention is ideally suited for, and produces important new and useful results when embodied in, relatively heavy or ponderous printing apparatus. The apparatus selected for illustration of the invention consists of a printing press comprising a printing couple and a feeder therefor. The press may be of any type but is shown as of the flat bed and cylinder type. The feeder likewise may be of any type but is shown as one which automatically lifts a pile of sheets during operation of the press and feeds the sheets singly from the top of the pile to the press. The press and feeder are made separable so that when printing is not being done and it is desired to work on the form or other parts of the press the feeder may be retracted away from the press to an out of the way inoperative position. To this end I preferably provide for relative rectilinear movement between the press and feeder. While either may be stationary or both may be movable relatively to the floor I prefer to mount the press stationarily and

2

to move the feeder toward and from the press. Thus when the feeder is moved out to inoperative position away from the press there is room for workmen to stand between the press and the feeder to work on the press or, if desired, on the feeder.

In the illustrated embodiment of the invention the press and feeder may be considered as relatively heavy or ponderous. Considerable force is required to move the feeder toward and from the press. It may, for example, carry a stack of sheets weighing thousands of pounds in addition to its own substantial weight. I preferably employ screw means for moving the feeder toward and from the press. I provide a screw connected with the feeder and a nut connected with the press and threadedly receiving the screw and means relatively turning the screw and nut. I have found that when moving means of this character is employed there is danger of locking of the screw means if the feeder is driven thereby up against and in contact with the press. Even though a powerful motor may be used the screw means may thus be so tightly locked that the motor will not operate in either direction and the apparatus has to be disassembled and reassembled with the parts in operative relation. To avoid this difficulty when employing the screw drive I utilize means for stopping movement of the feeder toward the press just prior to contact between the feeder and press. Such means may conveniently comprise a limit switch breaking the motor circuit. I also preferably employ a limit switch for limiting outward movement of the feeder. The limit switch for limiting inward movement of the feeder is preferably set so that under any condition of loading the feeder will never forcibly strike the press. Not only is this disadvantageous from the standpoint of locking the moving means but it may result in damage to the press or feeder or both.

Since I preferably stop the movement of the feeder toward the press before it fully reaches operative position relatively to the press I preferably provide means for drawing the feeder up tightly against the press into operative position. In order that such means may operate without disconnecting the power operated moving means I preferably provide a lost motion connection permitting drawing of the feeder up against the press without the necessity of disconnecting any part of the apparatus. Also when heavy or ponderous apparatus is employed the load on the motor is very heavy if it be attempted to start the motor from rest under full load, necessitating use of a

motor of large size. I find that I can use a motor of considerably smaller size and less capacity by providing for starting up the motor before movement of the feeder commences so that the motor will be up to speed when the full load is applied to it. The lost motion connection above mentioned preferably enables the motor to start before relative movement between the feeder and press commences. I find it convenient to mount the screw and nut on the press and feeder so that the nut may have limited movement in a direction parallel to the axis of the screw. In the structure shown in the drawings the screw is fastened non-rotatively to the feeder and the nut is mounted in the press. An electric motor is also mounted in the press for turning the nut. The nut is mounted in a collar and provision is made for limited lost motion of the nut in the collar in a direction parallel to the axis of the screw. As above mentioned, this enables the feeder to be drawn up tightly against the press without disconnecting the driving mechanism and also enables the motor to get up to speed before taking the full load when the feeder is to be moved toward or away from the press.

I preferably mount the means for relatively moving the portions of the apparatus so that the part of such means which is connected with one of said portions is connected therewith loosely so as to be free to partake of limited movement in any direction and especially transversely of the direction of relative movement between said portions. Preferably a transverse lost motion connection is provided between said part and the portion of the apparatus which carries it. In the structure shown in the drawings the screw is carried by a bracket which is loosely mounted on a portion of the feeder frame which allows the screw to shift slightly during operation. Any irregularities in the parts, as, for example, slight bending of the screw, are thus compensated for. There is some relative deflection and settling between the feeder and the press during and at the end of relative movement therebetween which tends to cause binding of the screw and nut and the loose mounting of the screw on the feeder frame obviates such tendency.

I preferably employ a slippable connection, such as a friction connection, between the motor and the moving means so that if a workman should be in between the feeder and press when the feeder moves toward the press and become caught therebetween the added resistance to movement will simply result in slippage of the connection whereby crushing of the workman will be avoided. This connection is also of advantage in case tools are left between the feeder and press which would result in damage if the feeder were positively moved despite the amount of resistance interposed. I find it desirable to employ a friction belt drive for the feeder, although other friction or slippable drives may be used.

I provide apparatus comprising portions relatively movable toward and from cooperative relation in which they are adjacently positioned, first moving means for relatively moving said portions, means operated by at least one of said portions, when said portions upon relative movement toward each other reach predetermined relative positions, for rendering inoperative said first moving means and stopping relative movement of said portions while they are still slightly spaced apart, whereby to avoid their striking forcibly together, and second moving means operable upon said stopping of said relative movement to further

relatively move said portions toward each other into cooperative relation. Preferably the first moving means comprises cooperating members, one connected with each portion, and an operating member connected with one of the cooperating members and operable to travel relatively to the other thereof whereby to relatively move said members and hence said portions, said operating member being movable relatively to the one of said cooperating members with which it is connected upon relative movement of said portions toward each other into cooperative relation by the second moving means.

Other details, objects and advantages of the invention will become apparent as the following description of a present preferred embodiment thereof proceeds.

In the accompanying drawings I have shown a present preferred embodiment of the invention, in which

Figure 1 is a fragmentary side elevational view of a sheet feeder shown in operative relation to a flat bed and cylinder printing press;

Figure 2 is a view similar to Figure 1 but showing the feeder moved out to inoperative position relatively to the press;

Figure 3 is a fragmentary horizontal cross-sectional view to enlarged scale taken on the line III—III of Figure 1;

Figure 4 is a fragmentary vertical longitudinal cross-sectional view taken on the line IV—IV of Figure 3;

Figure 5 is a fragmentary horizontal cross-sectional view of a portion of the structure as shown in Figure 1;

Figure 6 is a fragmentary longitudinal cross-sectional view to enlarged scale, with a portion cut away, the screw for moving the feeder toward and from the press and its cooperating mechanism;

Figure 7 is a vertical transverse cross-sectional view taken on the line VII—VII of Figure 6; and

Figure 8 is a vertical transverse cross-sectional view to enlarged scale taken on the line VIII—VIII of Figure 5.

Referring now more particularly to the drawings, there is shown at 2 a cylinder of a printing press. The press may be considered as a press of the flat bed and cylinder type to which sheets are fed singly in well known manner. The cylinder 2 and the flat bed cooperating therewith constitute the printing couple. Since the specific structure of the press or printing couple forms no part of the present invention such structure is not shown in detail.

Reference numeral 3 designates generally a feeder adapted to cooperate with the press to feed sheets thereto. The feeder is preferably movable between operative and inoperative positions relatively to the press upon rails 4 which extend out in a straight line from the feeder end of the press. Thus the feeder is movable rectilinearly into and out of operative position relatively to the press. In Figure 1 the feeder is shown in operative position and in Figure 2 it is shown moved out to inoperative position. When the feeder is in the inoperative position as shown in Figure 2 it provides a substantial space between the press and feeder, allowing workmen to enter and work upon the press or feeder.

Reference numeral 5 designates a portion of the feeder frame which extends downwardly to a position close to the floor where it has a horizontal extension 6. Fastened to the extension 6 by screws 7 is a bracket 8 having a cylindrical horizontal recess 9 bored therein. The bracket 8 has

two vertical bores 8a therethrough each of which loosely receives a sleeve 7a whose length is somewhat greater than the thickness of the bracket 8, the screws 7 extending within the respective sleeves 7a. A washer 7b lies between the head of each screw 7 and the top of the corresponding sleeve 7a and the screws are screwed down tight into the extension 6 so that the sleeves are fixedly positioned relatively to such extension. By reason of the fact that the internal diameter of each bore 8a is materially greater than the external diameter of the sleeve 7a therein and the fact that the length of each sleeve 7a is materially greater than the thickness of the bracket 8 such bracket, although held to the extension 6 by the screws, is free to partake of limited movement in any direction relatively to the extension. The reason for thus mounting the bracket will presently appear.

A screw 10 has integral with one end a projection 11 which enters the recess 9 in the bracket 8. A set screw 14 threaded into the top of the bracket 8 and intersecting the recess 9 engages the projection 11 of the screw 10 to hold the screw fixedly relatively to the bracket. After the screw 10 is thus held relatively to the bracket by the set screw 14 a tapered bore 13 is formed in the bracket 8 and projection 11 and a tapered pin 12 is driven thereinto to insure permanent proper relative positioning of the screw and bracket. After insertion of the pin 12 the set screw 14 may be removed if desired.

A portion of the press frame is shown at 15. Bolted to the press frame by bolts 16 is a collar 17 which at all times is fixedly positioned relatively to the press frame. Provision is made for adjusting the position of the collar 17 relatively to the press frame, but the collar in any adjusted position is immovably fixed to the press frame. A nut 18 is in threaded engagement with the screw 10 and has an elongated cylindrical outer surface 19 whose diameter is slightly smaller than the internal diameter of the collar 17 so that the nut may slide within the collar in the axial direction. The nut has an integral flange 20 at one end and at the other end has connected therewith by screws 21 a pulley or sheave 22. Thus the nut 18 is in effect flanged at both ends but, as clearly shown in Figure 6, the axial distance between the inner surfaces of the flanges is substantially greater than the thickness of the collar 17 in the axial direction so that the collar allows limited axial movement of the nut relatively thereto, such axial movement being limited in one direction by engagement of the flange 20 with the collar and in the other direction by engagement of the sheave 22 with the collar.

Mounted on the press frame is an electric motor 23 having a shaft 24 carrying a pulley 25. A friction belt 26 shown as being in the form of a V-shaped flexible composition belt extends about the pulleys 22 and 25 as clearly shown in Figure 5. The motor 23 is a reversible motor so that through the belt 26 it can turn the nut 18 in either direction. When the motor is operated to turn the nut in one direction after having last previously turned it in the opposite direction the nut will travel upon the screw 10 until either the flange 20 or the sheave 22, depending upon the direction of travel, engages the collar 17. During this travel of the nut the press and feeder will both remain stationary. Also during such travel of the nut the motor 23 will have time to get up to operating speed. As soon as the trailing flange of the nut (either the flange 20 or the sheave 22)

engages the collar 17 further travel of the nut along the screw 10 is positively prevented. Continued operation of the motor and turning of the nut then causes the screw 10 to travel axially since the screw is held against rotation in the feeder frame. Also since the screw is fixed to the feeder axial travel of the screw causes similar axial travel of the feeder upon the rails 4. The direction of travel of the feeder relatively to the 10 press depends upon the direction of operation of the motor 23 and the direction of turning by motor of the nut 18.

The loose or floating mounting of the bracket 8 on the feeder frame extension 6 allows for limited 15 relative movement between the bracket and the feeder frame which in turn allows the screw 10 to shift slightly during operation due to any slight irregularities of the parts or, for example, in the event that the screw 10 should become slightly bent. Also there is some relative deflection and settling between the feeder and the press during 20 and at the end of relative movement therebetween which, if the bracket 8 were rigidly attached to the feeder frame extension 6, would result in a tendency of the screw 10 to bind with the nut 18. Any such tendency to bind is obviated and any 25 slight irregularity of the parts is compensated for by the loose or floating mounting of the bracket 8 upon the feeder frame extension 6.

30 Connected to the outer end of the screw 10 is a bracket 27 carrying a limit switch operating cam 28. The cam 28 is connected with the bracket by bolts 29 which pass through an elongated slot 30 in the cam whereby the cam may be 35 adjusted along the bracket axially of the screw. Carried by the press frame are two limit switches 31 and 32. The limit switch 31 has an operating arm 33 and the limit switch 32 has an operating arm 34. The operating arms of the limit switches 40 are in longitudinal alignment and in the path of movement of the cam 28 as the feeder moves along the rails 4. The limit switches 31 and 32 are connected into the circuit for operating the 45 electric motor 23 in such manner that when the 50 motor is turning in the direction to move the feeder toward the press (toward the left viewing Figure 5) the cam 28 will operate the limit switch 31 to open the motor circuit just as the feeder is 55 reaching the position in which it is to be stopped, and when the motor is turned in the direction to move the feeder away from the press (toward the right viewing Figure 5) the cam 28 will operate the limit switch 32 to open the motor circuit just as the feeder is reaching the position in which it 60 is to be stopped.

The parts are so related that when the feeder 65 is moving toward the press the limit switch 31 operates to open the motor circuit in time so that the feeder under any condition of loading 70 will always stop before forcibly striking the press. The feeder may gently touch the press, but as a rule the limit switch will operate soon enough so that when the feeder stops it will be spaced from the press a fraction of an inch. Thus binding 75 of the screw and nut is prevented. Also, when the feeder is moving away from the press the limit switch 32 will prevent overtravel of the feeder and insure its always stopping in approximately the same position when moved to inoperative 80 position.

A portion of the feeder frame is shown at 35 (see Figure 3). A shaft 36 is mounted for rotation in the feeder frame, passing through the portion 35 and extending transversely of the 90 feeder and also being journaled in the opposite

frame portion. Keyed to the shaft 36 adjacent each side of the feeder is an eccentric 37. A latch 38 having a hook end 39 is mounted about each of the eccentrics 37, each of such latches having a hub portion 40 receiving the eccentric. Each of the feeder side frames carries a pin 41 which prevents the latch adjacent that side of the feeder from falling down. Each latch hub 48 carries a pin 42 extending parallel to the shaft 36. Integral with each of the eccentrics 37 is a collar 43 carrying a radial pin 44. At each side of the press frame is a projection 45 receiving a screw 46. Each of the screws 46 lies horizontally with its head away from the feeder. Keyed to the shaft 36 outside one of the side frames is an operating handle 47 for turning the shaft 36. The handle 47 has a hub 48 having two opposed shoulders 49 and 50. A pin 51 is connected with the side frame and projects outwardly therefrom in the path of the shoulders 49 and 50 when the handle 47 is moved about the axis of the shaft 36.

As explained above, when the feeder has been in its outward or inoperative position and is to be moved to operative position relatively to the press the motor 23 is operated to turn the nut 18 in such direction as to move the feeder toward the press. Such movement is terminated by opening of the limit switch 31 by the cam 28. This is done at such time, as above explained, that the feeder comes to rest a short distance away from the press.

Preferably when the feeder is moved up to its position spaced slightly from the press as thus described the handle 47 and latches 38 are in the position shown in Figure 1 but with the latches in a slightly lower angular position resting upon the respective pins 41. The function of these pins, as above explained, is simply to keep the latches 38 from falling down so low that they will not properly enter into engagement with the projections 45 of the press. As the feeder approaches the press the inclined nose surfaces 52 of the latches 38 ride up on the respective projections 45 but the hooks 39 do not quite reach the position shown in Figure 1 since the feeder is somewhat spaced from the press.

With the parts positioned as just explained the pressman moves the handle 47 in the clockwise direction, viewing Figure 1, through a small angle. As the parts are shown in Figure 1 the eccentrics 37 are approximately on dead center away from the projections 45 of the press. Consequently turning of the handle 47 in the clockwise direction tends to swing the eccentrics downwardly and toward the press, thus pushing the latches 38 toward the left viewing Figure 1. The latches will drop into position with their hooks against the heads of the screws 46, whereafter the handle 47 is returned to the position of Figure 1 by moving it in the counter-clockwise direction about the axis of the shaft 36. This returns the eccentrics 37 to their dead center positions and draws the feeder tightly up against the press. The screws 46 may be adjusted as desired to insure proper drawing up of the feeder against the press.

When the feeder is to be moved away from the press the handle 47 is turned in the clockwise direction viewing Figure 1 until the shoulder 49 engages the pin 51, as shown in Figure 2. The first part of the turning movement of the handle 47 swings the eccentrics 37 downwardly and toward the left as above explained, thus loosening the latches 38, and when the pins 44 engage the respective pins 42 the latches are lifted to the

position shown in Figure 2. The pins 44 engage the pins 42 shortly before the shoulder 49 engages the pin 51 and not until after the eccentrics have been turned far enough to loosen the latches. The feeder is then free to be moved away from the press, which, as above explained, is accomplished by operating the motor 23 in the direction to turn the screw 10 to move the feeder toward the right viewing Figure 1.

10 When the handle 47 is operated as above explained to draw the feeder up tightly against the press such relative movement between the feeder and the press is accompanied by movement of the screw 10 and nut 18 relatively to the collar 17, 15 the lost motion between the collar and the nut being sufficient to allow of tightening up of the feeder to the press as explained. When the motor 23 is stopped after moving the feeder toward the press the flange 20 will be in engagement 20 with the collar 17 and the sheave 22 will be spaced from the collar 17. Consequently drawing up of the feeder toward the press allows the nut 18 to slide toward the left viewing Figure 6 within the collar 17. Preferably the sliding of the nut with- 25 in the collar is through a distance substantially less than the clearance provided between the nut and the collar so that when the feeder is positioned tightly against the press there is substantial clearance between the sheave 22 and the col- 30 lar 17. This clearance is desirable so that when the motor is subsequently operated to move the feeder away from the press the motor will have time to get up to speed before the sheave 22 en- 35 gages the face of the collar 17. As the parts are shown in Figure 6 the sheave 22 is flush against the collar 17, this being the position of the parts when the feeder is being moved out away from the press. The force moving the feeder away from the press is exerted between the right-hand face of the collar 17 and the left-hand face of the sheave 22 viewing Figure 6.

Due to the freedom of movement of the nut 18 within the collar 17 the belt 26 partakes of slight angular displacement between its position when the feeder is moving in and its position when the feeder is moving out. However, the length of the belt and its flexibility are such as to allow for this angular displacement. The belt may slip upon the pulley 22 when any obstruction is offered to movement of the feeder. Thus if a workman is in between the press and the feeder when the feeder is moved toward the press the resistance imposed by the workman's body will result in slippage of the belt 26 and avoid serious injury to the man. Similarly, injury to the apparatus due to leaving tools or other obstructions between the press and the feeder is avoided by reason of the provision of the belt 26.

60 The drawings show, in some cases more or less diagrammatically or fragmentarily, other elements of the apparatus, but since such other elements may be conventional and do not form part of the present invention they will not be described in detail. It is of course to be understood that means are provided in the feeder for taking sheets from the top of the pile in the feeder and feeding them one by one to the press, after which they pass to a suitable delivery and are piled up. 65 The pile support in the feeder is shown at 53, the pile of sheets being omitted for the sake of clarity. Means are provided for raising the pile support, such means preferably being of the type described and claimed in Patent No. 2,334,223. 70 The sheets are moved down the feed board shown

at 54 and registered to the press in a manner known in the art.

While I have shown and described a present preferred embodiment of the invention it is to be distinctly understood that the invention is not limited thereto but may be otherwise variously embodied within the scope of the following claims.

I claim:

1. Apparatus comprising portions relatively movable toward and from cooperative relation in which they are adjacently positioned, first moving means for relatively moving said portions, means operated by at least one of said portions, when said portions upon relative movement toward each other reach predetermined relative position, for rendering inoperative said first moving means and stopping relative movement of said portions while they are still slightly spaced apart, whereby to avoid their striking forcibly together, and in such relative positions that the second moving means hereafter mentioned may become operative and second moving means to further relatively move said portions toward each other into cooperative relation, said first moving means comprising a screw connected with one of said portions, a collar connected with the other of said portions and through which the screw passes, a nut in threaded engagement with the screw and positioned within the collar, means for limiting relative movement between the nut and the collar axially of the screw and means for rotating the nut to cause relative travel between the nut and the screw axially of the screw whereby to relatively move said members and hence said portions, the nut being movable relatively to the collar axially of the screw upon relative movement of said portions toward each other into cooperative relation by said second moving means.

2. Apparatus comprising portions relatively movable toward and from cooperative relation in which they are adjacently positioned, first moving means for relatively moving said portions, means operated by at least one of said portions, when said portions upon relative movement toward each other reach predetermined relative position, for rendering inoperative said first moving means and stopping relative movement of said portions while they are still slightly spaced apart, whereby to avoid their striking forcibly together, and in such relative positions that the second moving means hereafter mentioned may become operative and second moving means to further relatively move said portions toward each other into cooperative relation, said first moving means comprising a screw connected with one of said portions, a collar connected with the other of said portions and through which the screw passes, a nut in threaded engagement with the screw and positioned within the collar, the nut having flange means adapted to engage the collar upon relative movement between the nut and the collar axially of the screw whereby to limit such relative movement, and means for rotating the nut to cause relative travel between the nut and the screw axially of the screw whereby to relatively move said members and hence said portions, the nut being movable relatively to the collar axially of the screw upon relative movement of said portions toward each other into cooperative relation by said second moving means.

3. Apparatus comprising portions relatively movable toward and from cooperative relation in which they are adjacently positioned, first mov-

ing means for relatively moving said portions, said first moving means comprising a screw connected with one of said portions, a collar connected with the other of said portions and through which the screw passes, a nut in threaded engagement with the screw and positioned within the collar, means for limiting relative movement between the nut and the collar axially of the screw and means for rotating the nut to cause relative travel between the nut and the screw axially of the screw whereby to relatively move said members and hence said portions, means operated by at least one of said portions, when said portions upon relative movement toward each other reach predetermined relative position, for rendering inoperative said nut rotating means and stopping relative movement of said portions while they are still slightly spaced apart, whereby to avoid their striking forcibly together, and in such relative positions that the second moving means hereafter mentioned may become operative and second moving means to further relatively move said portions toward each other into cooperative relation, the nut being movable relatively to the collar axially of the screw upon relative movement of said portions toward each other into cooperative relation by said second moving means.

4. Apparatus comprising portions relatively movable toward and from cooperative relation in which they are adjacently positioned, first moving means for relatively moving said portions, said first moving means comprising a screw connected with one of said portions, a collar connected with the other of said portions and through which the screw passes, a nut in threaded engagement with the screw and positioned within the collar, the axial dimension of the nut being greater than the axial dimension of the collar, the nut having flanges extending transversely of its axis the inner faces of which are spaced apart a distance greater than the axial dimension of the collar, and means for rotating the nut to cause relative travel between the nut and the screw axially of the screw whereby to relatively move said members and hence said portions, means operated by at least one of said portions, when said portions upon relative movement toward each other reach predetermined relative position, for rendering inoperative said nut rotating means and stopping relative movement of said portions while they are still slightly spaced apart, whereby to avoid their striking forcibly together, and in such relative positions that the second moving means hereafter mentioned may become operative and second moving means to further relatively move said portions toward each other into cooperative relation, the nut being movable relatively to the collar axially of the screw upon relative movement of said portions toward each other into cooperative relation by said second moving means.

5. Apparatus comprising portions relatively movable toward and from cooperative relation in which they are adjacently positioned, first moving means for relatively moving said portions, said first moving means comprising a screw connected with one of said portions, a collar connected with the other of said portions and through which the screw passes, a nut in threaded engagement with the screw and positioned within the collar, means for limiting relative movement between the nut and the collar axially of the screw and means for rotating the nut to cause relative travel between the nut and the

11

screw axially of the screw whereby to relatively move said members and hence said portions, means operated by at least one of said portions, when said portions upon relative movement toward each other reach predetermined relative position, for rendering inoperative said nut rotating means and stopping relative movement of said portions while they are still slightly spaced apart, whereby to avoid their striking forcibly together, and in such relative positions that the second moving means hereafter mentioned may become operative and second moving means operable when said portions have been brought into slightly spaced apart relation as aforesaid to further relatively move said portions toward each other into cooperative relation, the nut being movable relatively to the collar axially of the screw upon relative movement of said portions toward each other into cooperative relation by said second moving means, said second moving means comprising means connected with one of said portions

15

20

12

for engaging the other portion, eccentric means for moving said last mentioned means generally in the direction of relative movement between said portions and manually operable means for turning said eccentric means.
